UNITED STATES PATENT OFFICE.

WYNN MEREDITH, OF ALAMEDA, CALIFORNIA, ASSIGNOR TO PETROLEUM RECTIFYING COMPANY, OF SAN FRANCISCO, CALIFORNIA, A CORPORATION OF CALIFORNIA.

DEHYDRATOR.

Application filed October 28, 1920. Serial No. 420,245.

To all whom it may concern:

Be it known that I, WYNN MEREDITH, a citizen of the United States, and resident of the city and county of Alameda, State of California, have invented new and useful Improvements in Dehydrators, of which the following is a specification.

My invention has for its object the circulating of the emulsion in dehydrators for the purpose of effecting a more efficient treatment than heretofore. This I accomplish by causing the emulsion in the treatment chamber of the dehydrator to circulate in a path of electrical discharge, and I prefer to vary the length of the path in different portions of the treated emulsion such that in those parts of the body of emulsion which contains an increased water content the path of discharge will be longer.

Other objects will appear from the drawing and specification which follow.

By referring to the accompanying drawing my invention will be made clear:

Fig. 1 is a cross-section through one form of my dehydrator.

Fig. 2 illustrates a different arrangement of apparatus whereby the circulation is effected.

Fig. 3 is a plan view of Fig. 2.

Fig. 4 illustrates another form of circulating means whereby the circulation may be effected by direct action of the rotating electrode.

Throughout the figures similar numerals refer to identical parts.

Referring to Fig. 1. One of the electrodes is illustrated by the annular oppositely directed conical surfaces 1—2 between which the electrodes 3, 4, 5, 6 of opposite polarity are adapted to rotate. It is to be understood that electrical conductivity to the surfaces 1 and 2 is accomplished through the metallic structure of the dehydrator which may be grounded or in other well known ways.

These latter electrodes 3, 4, 5, 6, I prefer to form of rings held apart by bushings 7 carried upon supporting rods 8, the latter being suspended from the spider 9 which is connected with and operated by the shaft 10. The walls of the treatment chamber are shown at 11, and at 12 is indicated a propeller member actuated from the gearing 13 and driving shaft 14 and actuating pulley 15.

The chamber is suitably supplied with emulsion to be treated through the inlet pipe

16 which has a number of discharge openings as 17, 18, 19. The propeller is now set into operation by the driving pulley 15 actuated from the power means 20 such that the flow of emulsion will be in the direction of the arrows 21, 22 by the propeller and again up and around the passageway formed between the walls of electrode 1 and chamber 11, as indicated by the arrow 23, and again downward between the electrodes as indicated by the arrows 24 and 25. In this way the emulsion is subjected to a series of treatments between the electrodes; and so that the process of dehydration shall be continuous, oil is admitted in small quantities through the pipe 16 and outlets 17, 18, 19, and an equal amount is continuously withdrawn from the treatment chamber after it has received the electric treatment as at 37. In this way, while the process is continuous, any degree of electrical treatment may be obtained upon the entire body of the emulsion.

It will be noted that as the separation of the oil and water occurs within the treatment chamber that portion occupying the lower part of the chamber will contain a greater percentage of water than that portion of the emulsion in the upper part and consequently the electrical resistance of the upper part will be higher than in the lower part of the said treatment chamber. If now the path of electrical discharge as between the electrode ring 3 and the walls 1 and 2 is maintained the same distance as that between the electrode 6 and the said walls, there will be a greater discharge of current through the path of less resistance from 6 to 1—2 and therefore to equalize the resistance of paths of discharge I increase the said path between the electrodes at the lower portion of the treatment chamber, thus compensating for the difference in conductivity in the emulsion in its different positions in the container. It is to be understood that the employment of the propeller 12 of Fig. 1 within the container may be in any suitable location, and also as indicated in Fig. 4 the propeller 26 may be attached to and operated by the stem or shaft of the rotating electrode 27; in this case I prefer to admit the oil as through the pipe 28 to the said propeller, which latter is adapted to discharge the received emulsion in a radial direction as indicated by the arrows 29. In

this latter construction the supporting member for the electrodes may be formed with propeller blades or the propeller blades themselves may be employed to support the electrodes.

In Fig. 3 I have shown the circulation of the oil as being effected from an exterior source in which case the emulsion is successively passed between the electrodes by employing the circulating pump 30, which takes its emulsion from the one portion of the treatment chamber and thereafter passes it back into the treatment chamber, preferably in a line tangent with the walls of the treatment chamber. In this way the direction of circulation enables the centrifugal force of the oil being discharged into the chamber at 32 to separate in a measure the lighter from the heavier portions of the emulsion, thus subjecting the lighter portions to the action between the electrodes and facilitating the separation of the heavier portion which falls in the direction of the arrow 33 and accumulates more readily in the lower portion of the chamber as 34, from which it may be withdrawn at 37. (Fig. 1.)

In Fig. 2 at 35 I have shown an inlet funnel of relatively large dimensions compared with the feeder pipe 36, so that any circulation disturbances in the pipes 31 or 36 or the emission of any bubbles through the said pipes will find egress through the body of emulsion in 35 without ejecting any portion of the said emulsion therefrom, and the body of oil in the said inlet funnel forms a seal against the ingress of air, and therefore prevents the formation of an explosive mixture should the oil level tend to fall.

The chamber or container 11 is preferably made of metallic or other conducting material as are the suspension and supporting members 50, 51, and 52, for the electrodes 1 and 2, and it is also customary to ground said container as shown at 53. The circuit connections are shown at 54, 55 whereby the electrodes are energized, the container walls 56, 57, 11, serving as one leg of the circuit and connected with 54, and which container may be grounded at 53, and which through the suspension members 50, 51, energizes the electrodes 1 and 2. The other leg of the circuit 55 is connected with the rotatable electrodes 3, 4, 5, 6, through the insulated connections 10, 9, 7.

Reference is herein made to my co-pend-

ing applications Serial Numbers 420,244, 420,246 filed October 28, 1920.

I claim:

1. In combination with a treatment chamber for the dehydration of emulsions, a propeller for circulating said emulsion and driving means for said propeller, plates adapted to guide the circulation of said emulsion to direct it through a zone of treatment within said chamber, in combination with an electrode adapted to rotate between said plates. 60

2. Apparatus as set forth in claim 1, and an inlet for said emulsion before treatment and an outlet for said emulsion after it has 70 received treatment.

3. Apparatus as set forth in claim 1 wherein said electrode is disposed symmetrically between said plates and electric connections to said electrode and said plates respectively, and means for rotating said electrode. 75

4. Apparatus as set forth in claim 1 wherein the propeller is fixed to rotate with the electrode, and wherein the electrode is 80 symmetrically disposed between said plates.

5. Apparatus as set forth in claim 1 wherein the propeller is fixed to rotate with the electrode, and wherein said electrode is 85 symmetrically disposed between said plates, and electric connections for energizing said electrode and said plates.

6. Apparatus as set forth in claim 1 wherein the propeller is fixed to rotate with the electrode, and wherein said electrode is 90 symmetrically disposed between said plates, and electric connections for energizing said electrode and said plates, and means constructed and adapted to rotate said electrode.

7. In combination with a chamber for the electrical treatment of emulsions, a circulating pump a duct from said chamber to said pump, a second duct from the discharge side of said pump to said chamber entering said chamber substantially tangent to the 100 said chamber.

8. In combination with a chamber for the electrical treatment of emulsions, a circulating pump a duct from said chamber to said pump, a second duct from the discharge 105 side of said pump to said chamber, and entering said chamber substantially tangent to the said chamber.

WYNN MEREDITH.
